UNITED STATES PATENT OFFICE.

JACOB J. ALBRIGHT, OF COLUMBUS, GEORGIA.

REGISTER.

1,417,011.

Specification of Letters Patent. Patented May 23, 1922.

Application filed December 7, 1920. Serial No. 428,910.

To all whom it may concern:

Be it known that I, JACOB J. ALBRIGHT, a citizen of the United States, residing at Columbus, in the county of Muscogee and 5 State of Georgia, have invented certain new and useful Improvements in Registers; and I do hereby declare the following to be a full, clear, and exact description of the invention, such as will enable others skilled 10 in the art to which it appertains to make and use the same.

This invention relates to improvements in actuating and reset mechanism for counter groups, and more particularly to such as are 15 especially adapted for registering the quantity of liquid being delivered to or consumed at a given point, as, for example, the measuring of liquid fuel for internal combustion engines.

20 The object in view is the effective and accurate delivery, to a counter group, of motion from an actuator through devices susceptible of release for facilitating reset of the counters.

25 A more detail object is the facilitating of adjustment of the release mechanism to and from the position admitting of adjustment of the counters.

30 A still further object is the insurance of synchronous action of two counter groups with respect to each other while providing easily manipulated means for releasing one counter group with respect to the other for enabling independent adjustment thereof.

35 With these and further objects in view as will in part hereinafter become apparent and in part be stated, the invention comprises certain novel constructions, combinations and arrangements of parts as subsequently specified and claimed.

In the accompanying drawings,—

Figure 1 is a fragmentary, front elevation of a mechanism embodying the features of the present invention.

45 Figure 2 is an edge view thereof, parts being broken away.

Figure 3 is a similar view to Figure 1 of the opposite side of the mechanism.

50 Figure 4 is an enlarged, detail section taken approximately on the plane indicated by line 4—4 of Figure 2, parts being broken away and parts being seen in elevation.

Figure 5 is a vertical section taken on the plane indicated by line 5—5 of Figure 4, and looking in the direction of the arrow, parts being broken away.

Figure 6 is a vertical section taken on the plane indicated by line 6—6 of Figure 4, and looking in the direction indicated by the arrows, parts being seen in elevation and parts 60 being broken away.

Figure 7 is a fragmentary view similar to a portion of Figure 4, but showing the synchronizing gear thrown out of clutch.

Figure 8 is a vertical section taken on the 65 plane indicated by line 8—8 of Figure 7, and looking in the direction indicated by the arrow, parts being seen in elevation.

Figure 9 is a detail section taken on the plane indicated by line 9—9 of Figure 7, 70 parts being seen in elevation.

Figure 10 is an edge view of the outer clutch member detached, the spring clutch being shown in position.

Figure 11 is a detail, perspective view of 75 one of the counter actuating sleeves detached.

Figure 12 is an enlarged, detail, fragmentary edge view of the synchronizing gears and co-operating parts, parts being broken 80 away and the cam shaft being shown in section at one of its cams.

Figure 13 is a perspective view of the cam shaft detached.

Figures 14, 15 and 16 are views similar 85 respectively to Figures 1, 2 and 12 of a slightly different embodiment of the invention.

Referring to the drawings by numerals, 1 indicates an exterior casing or shell having a finishing plate or flange 2 surrounding the front end of the casing. A sheet of glass or other transparent plate 3 closes the front end of casing 1 and is rendered opaque by painting or otherwise except at points 95 3', 3'', where the counter groups are exposed. An annulus 5 is fixed in the inner end of casing 1 in any appropriate manner and carries a bracket plate 4 within the casing 1, the plate 4 being secured to annulus 90 5 by screws 5', and an edge portion of the plate 4 being turned outward to form a bearing bracket 9 hereinafter mentioned. The rear face of annulus 5 carries a vacuum chamber or housing 6 which contains the 105 impulse-imparting mechanism not herein shown, and forming part of the subject matter of my co-pending application Serial No. 215,622, filed February 6, 1918.

Journalized in a bracket 7 outstanding from 110 plate 4 is a shaft 8 which also extends laterally through the bracket 9. Shaft 8 may be

considered the power shaft since it receives impulses from an actuator hereinafter described and operated proportionately to the delivery of fluid being measured. Counter 5 wheels 10, 10 forming a counter group, are mounted on the shaft 8 and are connected by the usual gearing of the ordinary counter group mechanism, whereby movement of the first wheel to the right throughout a complete revolution effects one step of advance 10 of the adjacent wheel to the left, and so on throughout the counter group. As this counter mechanism is of the ordinary commercial type, it is not specifically shown 15 herein. A sleeve 11 surrounds shaft 8 and extends through bracket 9 so as to form a bearing for the shaft 8, the sleeve in turn finding bearing in the bracket. The inner end of sleeve 11, that is, the end adjacent 20 the counter group, is provided with a terminal disc 12 formed about its periphery with serrations producing substantially a circular rack shaped to fit the teeth of an internal gear 13 formed in the inner periphery of the counter wheel 10 at the extreme 25 right. It is understood, of course, that each counter wheel 10 is provided with internal gear teeth, such as seen at 13, for intermeshing with the motion transfer mechanism 30 from one counter wheel to the next, and the arrangement of the disc 12 on sleeve 11 with its teeth interlocking with teeth 13 is merely a convenient manner of rigidly connecting the sleeve 11 to the counter wheel 10, so that 35 the counter wheel will revolve with the sleeve. Sleeve 11, at its outer end portion, has longitudinal notches 14, 14, leaving outstanding prongs or fingers 15, 15. A gear 40 wheel 16 is mounted on the outer end portion of the shaft 8 in position for sliding longitudinally of the shaft, the gear wheel being formed with radial notches 17, 17, proportioned and arranged to accommodate the fingers 15, so that the gear 16 is free to slide 45 laterally with respect to itself and longitudinally of the shaft and along said fingers, being limited in such movement in the direction toward the counter group by the walls of the sleeve 11 at the inner terminus of 50 the notches 14, and in its outward movement by parts hereinafter described. The bore of sleeve 11 is enlarged at the outer end portion of the sleeve forming a shoulder 18, and leaving a space about the shaft 8 from 55 said shoulder to the outer end of the sleeve. A spring 19 is coiled about the shaft 8 within the space thus formed, and has its inner end resting against the shoulder 18 and its outer end engaging the gear wheel 16 and 60 stressing the same outward. The outer face of gear wheel 16 is formed with clutch teeth 20, facing a co-operating clutch member 21, having similar teeth adapted to intermesh 65 with the teeth 20 when the clutch plate 21 and the clutch face of gear 16 are brought

into engagement. The clutch plate 21, at that face opposite its clutch teeth, is provided with an outstanding boss or drum 22, about which is coiled a clutch spring 23, the spring snugly fitting the surface of the 70 drum, and having one end left free while the other end is bent to form an outstanding projection 24. Near the outer end of the shaft 8 a cross pin 25 is passed through the shaft in position to lie in radial notches 26, 75 26, formed in the inner face of the clutch plate 21, so that when the shaft 8 is revolved the plate 21 moves with it, the clutch spring 23 allowing free rotation of the clutch plate in one direction but having its projecting 80 end 24 anchored to a relatively fixed part hereinlater mentioned for preventing movement of the clutch plate 21 when the latter is stressed angularly in the direction tending to wind the spring 23. The clutch plate 21 85 with its drum 22 is mounted on the outer end portion of shaft 8 in such position that when the pin 25 rests in the notches 26, the outer face of drum 22 will be substantially flush 90 with the outer end of the shaft 8.

Extending through and rotatably mounted in the bracket 9 is a sleeve 11' structurally identical with sleeve 11 and arranged parallel thereto, and provided with a disc 12' having rack teeth interlocked with the internal gear teeth of a counter wheel 10', being one of a group of counter wheels indicated by 10', 10'. The counter wheels 10', 10' are mounted on a shaft 8', which is journaled at its inner end portion in a bracket 100 outstanding from plate 4. The shaft 8' while for convenience of construction is thus journaled, may so far as its operation is concerned be fixed to its supporting bracket. The shaft 8' extends throughout the length 105 of sleeve 11' and bears the same proportional relation to the sleeve as does shaft 8 with respect to sleeve 11. The outer end portion of sleeve 11' is constructed identically the same as the outer end portion of sleeve 11, and 110 contains a spring 19' coiled about the shaft 8' and arranged to stress outwardly a gear wheel 16', the same in form as gear wheel 16, except that gear wheel 16' is not provided with clutch teeth and is not intended 115 to be shifted along the sleeve 11'. To prevent any accidental shifting of gear 16', a washer 27 surrounds the shaft 8' and is provided with radial notches corresponding to the radial notches in the gear wheel 16' for 120 accommodating the fingers at the outer end of sleeve 11', so that the spring 19' actually presses against the washer 27 instead of against the gear wheel 16'. The spring 19' functions merely to take up wear of the 125 parts and to allow a slight flexibility of the gear 16' when the gear 16 is being moved into mesh therewith under circumstances where the clutch teeth 20 do not accurately mesh with the teeth of clutch plate 21 when 130

being moved toward said plate. The arrangement of spring 19' and washer 27 also enables the use of the sleeve 11' in a form interchangeable with sleeve 11.

- 5 A frame 28 is arranged outside of the gear wheels 16, 16', and consists of an integral plate formed between the shafts 8 and 8' with a transversely arranged sleeve 29 and at each end with an enlargement, that opposite the clutch plate 21 being in the form of an annulus 30 surrounding the spring clutch 23. The material of the frame 28 is recessed at 31 to receive the laterally extending projection 24 of the spring 23, whereby 10 the spring is held against movement so that, owing to the snug fit of its several helices about drum 22, the said drum will be held against rotation in a direction tending to wind the spring 23 and is left free to rotate 15 in a direction tending to unwind the spring. To retain the frame in its given relation to the parts stated, a disc-like washer 32 overlies the enlargement 30 and covers the clutch spring 23 and clutch drum 22. The washer 20 32 is held in place by a screw 33, which is threaded into the outer end portion of the shaft 8. The opposite end portion of the frame 28 is formed with an enlargement 34 of greater proportions than the enlargement 25 30, taking the form substantially of a cross plate having its intermediate portion recessed at 35 for accommodating the outer end portion of the sleeve 11' and apertured for the passage of the outer end portion of the shaft 30 8', the frame 28 being anchored to the shaft by a bolt 36 threaded into the shaft and having a head engaging the outer face of the frame 28. Fixed to the outstanding end portions of the cross plate forming the enlargement 34 are spring rods 37, there being preferably two such rods, one above and one below the main portion of the frame 28 and extending substantially parallel thereto to points in front of the gear wheel 16. A ring 40 38 surrounds the clutch teeth 20 and rests normally with its inner edge against the outer face of the gear wheel 16, and the free ends of the spring rods 37 are fixed to the ring 38 so that movement of the free ends 45 of the spring rods 37 inward will stress the gear wheel 16 substantially uniformly about the wheel in an axial direction along the sleeve 11. Such stress being in excess of the pressure of spring 19, the gear wheel 16 will 50 be moved until its clutch teeth 20 free themselves from the teeth of clutch plate 21, and at the same time the gear teeth of wheel 16 will free themselves from the teeth of gear 16' so that both of said gear wheels may be 55 freely revolved, and as each is still interlocked with its respective sleeve the respective counter groups may be reset by revolution of the respective gear wheel while thus freed. When the stress is relieved from the 60 ring 38, and it is allowed to return to its

normal position under the spring action of rods 37, the spring 19 will return the gear wheel 16 to its former position and thus bring the clutch teeth 20 into engagement with the teeth of clutch plate 21 and also 70 bring the gear teeth of gear wheel 16 into mesh with the teeth of gear wheel 16', whereby the parts are connected for normal operation.

The spring rods 37 are designed to be deflected by camming means for stressing the ring 38 and thus moving the gear 16 out of mesh. The cam means may assume any of a variety of forms, and preferably consists of some form which will enable the same physical device serving to actuate the camming parts also to cause intermesh of gears enabling the camming actuator to be used for resetting the gears. To this end and for the purposes of the claims, the embodiment illustrated in Figures 14, 15 and 16, and to be hereinafter described in detail, is to be considered the preferred embodiment, but a simpler form of the camming mechanism is seen in Figures 2, 3, 12 and 13. 85 In this simpler form, the cam actuator has no connection with the gears. The cam actuator consists of a spindle or shaft 39 journalled in the sleeve 29, and extending through the flange or finishing plate 2, and 90 formed outside of said finishing plate with a knurled head 40 for facilitating manual manipulation. Head 40 prevents longitudinal movement of spindle 39 in one direction and a cotter pin 51 extends through the 100 spindle 39 in position to engage one end of sleeve 29 for preventing longitudinal movement of the spindle in the other direction. The spindle 39 is itself formed into a pair of cams 41, consisting merely in each instance of a notch or recess formed transversely of the spindle and arranged to lie normally in line with the spring rods 37, as seen in Figure 3, so that the spring rods may 105 extend in position for allowing the spring 19 to retain the gear 16 with its clutch teeth 20 in mesh with the teeth of clutch plate 21. When it is desired to reset the counter groups or either of them, it is only necessary to revolve the spindle 39 from the position shown in Figure 3 and in dotted lines in Figure 12 to the position shown in full lines in Figure 12, whereby the material of the spindle cams the spring rods 37 laterally and thus throws the gear 16 to the position for allowing a resetting operation. Converse movement of spindle 39 will, of course, allow return of gear 16 and if the gear 16 is positioned on return with its teeth 20 slightly out of line with the spaces 115 between the teeth of plate 21, a slight oscillation of the gear 16 will cause it to find its proper place and enable the clutch faces to close under the stress of spring 19. 120

As seen in Figure 1, the upper exposed 130

counter group may be considered the group indicating the quantity in gallons and tenth of gallons of hydro-carbon fuel in the supply tank, and the lower counter group as 5 indicating the total number of gallons and tenth of gallons of fuel already used. Since the lower group is actuated by the sleeve 11, its gear wheel 16 is the one which is thrown laterally out of mesh with the clutch plate 10 21 when the spring rods 37 are stressed for this purpose, the gear wheel 16' being left in its substantially fixed relation and being then free to rotate, the parts being in the relative position indicated in full lines in 15 Figure 12. By revolving the gear wheel 16' the upper counter group may be reset, and in actual practice, when the present improved mechanism is applied to an automobile or like device whose functions depend 20 upon the operation of an internal combustion engine, the upper counter group will be reset whenever a new or additional supply of fuel is delivered to the supply tank. Ordinarily it will not be necessary to reset 25 the lower counter group, since it will collectively indicate the total amount of fuel used, but such resetting may be accomplished readily when the parts are in the position indicated in full lines in Figure 12 by 30 merely revolving the gear wheel 16. In resetting the lower group of counter wheels, the desire ordinarily would be to return the group to zero so as to begin the count over again, but in resetting the upper counter 35 group the numerical value indicated by the upper counter group is increased to correspond with an increase in the supply of fuel, and, during operation, as the fuel is supplied to the engine, the actuation of shaft 40 8 will cause the sleeve 11 to revolve in a direction for increasing the numerical showing of the lower group and the consequent actuation of gear wheel 16' by gear wheel 16 will cause a reduction in the numerical 45 value of the upper group. Thus the actual amount of fluid fuel left in the tank will be indicated in the upper counter group by the process of subtraction while the actual amount consumed will be indicated by the 50 lower group by the process of addition.

By reference to Figure 4, the manner of delivery of motion through the several parts will become clear, it being seen that the drive shaft 8 receives its power from a clutch 55 drum 42 about which is coiled a clutch spring 43 having an outwardly turned end 44 extending into a notch in a clutch sleeve 45. The sleeve 45 surrounds the clutch spring 43 and is provided with an actuating arm 60 46, the clutch spring 43 operating identically the same as clutch spring 23, but in a converse direction. That is to say, when the arm 46 is swung angularly the movement of the sleeve in the direction tending to open 65 or uncoil the spring 43 will be in a direc-

tion tending to coil the spring 23 should the drum 42 and shaft 8 tend to follow the uncoiling movement of spring 43. As a matter of fact, there is no lost motion whatever in this inner clutch made up of the spring 70 43 and its co-operating parts, but the outer clutch made up of the spring 23 and its co-operating parts is provided to absolutely insure against any possible reverse motion of shaft 8. When the arm 46 is swung angularly in the direction for tending to coil or wind the spring 43, the drum 46 is gripped instantly and moved angularly identically the same distance as is the sleeve 45, the shaft 8 being advanced with the drum 80 42, and the outer clutch permitting such advance movement since that movement is in the direction tending to open or uncoil the spring 23. The arm 46 is swung angularly by a shaft 47 to which the arm 46 is pivoted 85 by a rod 48, the shaft 47 extending through the plates 4 and 5 to the impulse-delivering mechanism not herein disclosed and forming part of my co-pending application above identified, which impulse mechanism is actuated proportionally to quantities of fluid fuel delivered. The drum 42 may be fixed to the shaft 8 in any appropriate manner, but is preferably merely passed onto the shaft and locked thereto by a transverse pin 49 90 extending through the shaft 48 and lying in radial notches 50 formed in one face of the drum 42, and corresponding in construction and arrangement to the manner of the locking of the clutch plate 21 to the 100 shaft 8.

When an impulse is imparted from the rod 47 through the inner clutch to the shaft 8, the clutch plate 21 is advanced angularly the same distance as the advance of drum 105 42, and shaft 8, and the said clutch plate 21 imparts its motion to the gear wheel 16, which in turn imparts its motion to the sleeve 11, and the counter group actuated thereby. The gear wheel 16 also imparts its 110 motion to the gear wheel 16', but in a converse direction, so that sleeve 11' is advanced angularly identically the same distance but in a converse direction to the advance of sleeve 11, so that the counter group actuated 115 by sleeve 11' is moved in a direction for subtracting while the counter group actuated by sleeve 11 is moved in a direction for addition.

As a precaution against movement under 120 momentum, such as incident to a sudden thrust, the drum 42 is preferably restrained and held to its positive movement by an appropriate drag such, for example, as seen in Figures 4 and 5, in which is shown a disc 52 125 fixed to the drum 42 and outstanding therefrom beyond the sleeve 45. The periphery of disc 52 is preferably serrated and the end of a relatively thin spring plate 53 is caused to rest against the serrated edge under 130

spring pressure so as to insure against movement of the drum in either direction under sudden impulses and not consistent with and equal to the exact angular movement of the 5 sleeve 45. The spring 53 may be secured in place in any of various ways, but is preferably held by a screw 54 passed through a portion of the spring and threaded into the plate 4. To prevent possible pivotal movement of spring 53 on screw 54, the spring is 10 extended beyond the screw and turned substantially at right angles to form a projection 55 extending through an aperture 56 formed through the plates 4 and 5. 15 With the construction of camming device for shifting the reset wheels out of mesh and leaving them free for a resetting operation, it is necessary to leave a portion of each of the gears 16, 16' exposed as, for 20 instance, through apertures in the finishing plate or flange 2, so as to be accessible for manual manipulation. It is my intention, however, to provide means enabling the complete covering of these gear wheels as 25 seen in Figure 14, wherein the finishing plate 2^a is not provided with openings for the exposure of the reset wheels. Obviously, the finishing plate 2^a may be given a contour different from that shown as may be 30 found desirable. However, to enable the closing in of the reset wheels, gearing must be provided enabling the resetting at least of the wheel controlling the upper counter group, so as to enable the resetting of that 35 counter group whenever a fresh supply of fluid fuel is provided. To this end, the same identical mechanism is employed as above described, except as to the form of camming spindle and the addition of gears actuated thereby, so that the same reference 40 numerals are employed and the same description will apply to the structure seen in Figures 15 and 16 as that above described with the exception of said camming apparatus and its gears which will now be set forth in detail. Journaled on the stub shaft 57 which extends rearward from one end of the cross plate 34 is an idler pinion 58 constantly in mesh with the gear wheel 16'. A 45 spindle 39^a is slidingly mounted in the sleeve 29 and is provided with conical wedges 41^a, 41^a, corresponding in location to the location of the cam recesses 41 of spindle 39. The conical wedges 41^a, in operation, serve 50 to wedge the spring rods 37 for shifting the ring 38 and thus moving the gear 16' when the spindle 39^a is moved longitudinally as indicated in dotted lines in Figure 15. The spindle 39^a extends through the plate 2^a 55 and is formed with a knurled head 40^a for facilitating manual manipulation. The inner end of the spindle 39^a carries a gear wheel 59 which is fixed to the spindle and positioned for coming into mesh with the 60 idler pinion 58 when the spindle 39^a is 65

moved to the dotted line position of Figure 15, so that when the cams 41^a are in engagement with spring rods 37 and are holding the spring rods in their sprung position with the gear 16 out of mesh with gear 16', the 70 gear 59 will be in mesh with pinion 58. It is then only necessary for the operator to rotate the knurled head 40^a to effect rotation of gear wheel 16' and consequent resetting of the upper counter group. 75

What is claimed is:—

1. In registering mechanism, the combination with two counter groups, of intermeshing gear wheels, one connected to actuate one counter group and the other connected to actuate the other counter group, one of said gear wheels being shiftable relative to the other for being moved out of mesh therewith. 80

2. In registering mechanism, the combination with two counter groups, of intermeshing gear wheels, one connected to actuate one counter group and the other connected to actuate the other counter group, one of said gear wheels being shiftable relative to the other for being moved out of mesh therewith, and elastic means normally stressing the shiftable gear wheel toward a position in mesh with the other gear wheel. 90

3. In registering mechanism, the combination with two counter groups, of intermeshing gear wheels, one connected to actuate one counter group and the other connected to actuate the other counter group, one of said gear wheels being shiftable relative to the other for being moved out of mesh therewith, and means for driving one of the gear wheels relative to quantities of substance to be counted for effecting registration by both counter groups. 100

4. In registering mechanism, the combination of a shaft adapted to be actuated proportionally to quantities of substance to be counted, a gear wheel actuated thereby, a counter group actuated by the gear wheel, 110 a second gear wheel in mesh with the first gear wheel, and a counter group actuated by the second gear wheel.

5. In registering mechanism, the combination of a shaft adapted to be actuated proportionally to quantities of substance to be counted, a gear wheel actuated thereby, a counter group actuated by the gear wheel, 115 a second gear wheel in mesh with the first gear wheel, and a counter group actuated by the second gear wheel, one of the gear wheels being shiftable mounted for being moved out of mesh with the other gear wheel. 120

6. In registering mechanism, the combination of a shaft adapted to be actuated proportionally to quantities of substance to be counted, a gear wheel actuated thereby, a counter group actuated by the gear wheel, 125 a second gear wheel in mesh with the first gear wheel, and a counter group actuated 130

by the second gear wheel, the first-mentioned gear wheel being movably mounted on the shaft to and from a position in mesh with the second-mentioned gear wheel.

- 5 7. In registering mechanism, the combination of a shaft adapted to be actuated proportionally to quantities of substance to be counted, a gear wheel actuated thereby, a counter group actuated by the gear wheel, 10 a second gear wheel in mesh with the first gear wheel, a counter group actuated by the second gear wheel, and means for shifting the movable gear wheel out of mesh with the other.

- 15 8. In registering mechanism, the combination of a shaft adapted to be actuated proportionally to quantities of substance to be counted, a gear wheel actuated thereby, a counter group actuated by the gear wheel, 20 a second gear wheel in mesh with the first gear wheel, a counter group actuated by the second gear wheel, one of the gear wheels being shiftably mounted for being moved out of mesh with the other gear wheel, and 25 means for shifting the first-mentioned gear wheel along its drive shaft out of mesh with the second-mentioned gear wheel.

9. In registering mechanism, the combination of a power shaft adapted to be actuated relative to quantities of substance to be counted, a sleeve on said shaft and rotatable independently thereof, a gear wheel mounted on the shaft and connected with the sleeve to rotate therewith, a clutch connection 30 between the shaft and the gear wheel for causing the gear wheel to rotate with the shaft, a counter group actuated by the sleeve, a gear wheel meshing with the first-mentioned gear wheel, and a counter group actuated by the second-mentioned gear wheel, the clutch connection being adapted to be opened for allowing the first-mentioned gear wheel to rotate free of the shaft.

10. In registering mechanism, the combination of a power shaft adapted to be actuated relative to quantities of substance to be counted, a sleeve on said shaft and rotatable independently thereof, a clutch connection for causing the sleeve to rotate with the 45 power shaft, and a counter group actuated by the sleeve, the clutch connection being adapted to be opened for releasing the sleeve and freeing it to rotate independently of the shaft.

- 55 11. In registering mechanism, the combination of a power shaft adapted to be actuated relative to quantities of substance to be counted, a clutch actuated by the shaft, a counter group operated by the clutch, a 60 spring engaging the clutch and stressing the same toward its closed position, a cam engaging the spring for shifting the same for moving the clutch to an open position and leaving the counter group free for re- 65 setting, and gearing connected to be actu-

ated by the cam for resetting the counter group.

12. In registering mechanism, the combination of a power shaft adapted to be actuated relative to quantities of substance to be counted, a counter group, an actuator therefor, a clutch member engaging the actuator, a clutch member engaging the shaft and the first-mentioned clutch member for transmitting motion from the shaft to the actuator, 75 one of the clutch members being movable relative to the other for disengaging the clutch members, a second counter group, an actuator therefor, and means for transmitting motion from the first-mentioned clutch member to the last-mentioned actuator.

13. In registering mechanism, the combination of a power shaft adapted to be actuated relative to quantities of substance to be counted, a counter group, a sleeve mounted on the shaft and engaging the counter group for actuating the same, a clutch member movably mounted on the shaft, the sleeve having projections engaging the 85 clutch member for permitting movement of the clutch member longitudinally of the shaft and sleeve while preventing independent rotation of the clutch member with respect to the sleeve, and a clutch member 90 fixed to the shaft to move therewith and adapted to cooperate with the first-mentioned clutch member for transmitting motion from the shaft to the sleeve.

14. In registering mechanism, the combination of a power shaft adapted to be actuated relative to quantities of substance to be counted, a counter group, a sleeve mounted on the shaft and engaging the counter group for actuating the same, a clutch member movably mounted on the shaft, the sleeve having projections engaging the clutch member for permitting movement of the clutch member 100 longitudinally of the shaft and sleeve while preventing independent rotation of the clutch member with respect to the sleeve, a clutch member 105 fixed to the shaft to move therewith and adapted to co-operate with the first-mentioned clutch member for transmitting motion from the shaft to the sleeve, and 110 elastic means stressing the first-mentioned clutch member toward a position in clutch with the second mentioned clutch member.

15. In registering mechanism, the combination of a power shaft adapted to be actuated relative to quantities of substance to be counted, a counter group, a sleeve mounted on the shaft and engaging the counter group for actuating the same, a clutch member movably mounted on the shaft, the sleeve 120 having projections engaging the clutch member for permitting movement of the clutch member longitudinally of the shaft and sleeve while preventing independent rotation of the clutch member with respect to the 125 sleeve.

sleeve, a clutch member fixed to the shaft to move therewith and adapted to co-operate with the first-mentioned clutch member for transmitting motion from the shaft to the 5 sleeve, a second counter group and an actuator therefor adapted to be operated by engagement with the first-mentioned clutch member when the latter is in clutch with the second-mentioned clutch member.

10 16. In registering mechanism, the combination of a drive shaft adapted to be actuated relative to quantities of substance to be counted, a sleeve mounted on the shaft, a counter group actuated by the sleeve, a gear 15 wheel rotatably mounted on the shaft and having apertures, the sleeve having prongs extending into and fitting said apertures for allowing the gear wheel to be shifted along the shaft while preventing independent rotation of the gear wheel relative to the sleeve, the gear wheel having a clutch member, a co-operating clutch member on the shaft fixed to rotate therewith and adapted to have the clutch member of the gear wheel 20 move into and out of clutch, a gear wheel meshing with the first-mentioned gear wheel, and a counter group actuated by the second-mentioned gear wheel.

17. In registering mechanism, the combination of a power shaft adapted to be actuated relative to quantities of substance to be counted, a clutch actuated by the shaft, a counter group actuated by the clutch, a clutch shifting member, a spring arm carrying said member, and a cam adapted to be moved against the spring arm for shifting the member for opening the clutch and thus releasing the engagement between the shaft and counter group for enabling resetting of 40 the counter group.

18. In registering mechanism, the combination of a power shaft adapted to be actuated relative to quantities of substance to be counted, a clutch actuated by the shaft, 45 a counter group actuated by the clutch, a

ring positioned to contact with one member of the clutch, a pair of rigidly mounted spring arms engaging and sustaining the ring, and means for camming the arms to a position shifting the ring and thereby 50 moving the clutch member to an open position for releasing engagement between the drive shaft and the counter group for enabling resetting of the counter group.

19. In registering mechanism, the combination of a power shaft adapted to be actuated relative to quantities of substance to be counted, a clutch actuated by the shaft, a counter group actuated by the clutch, a ring positioned to contact with one member 55 of the clutch, a pair of rigidly mounted spring arms engaging and sustaining the ring, a spindle extending past said spring arms and having cams adapted to engage the same for moving the ring carried thereby 60 for shifting the clutch to an open position for releasing engagement between the drive shaft and the counter group.

20. In registering mechanism, the combination of a power shaft adapted to be actuated relative to quantities of substance to be counted, a clutch actuated by the shaft, a counter group actuated by the clutch, a ring positioned to contact with one member of the clutch, a pair of rigidly mounted spring arms 70 engaging and sustaining the ring, a spindle extending past said spring arms and having cams adapted to engage the same for moving the ring carried thereby 75 for shifting the clutch to an open position for releasing engagement between the drive shaft and the counter group, and means actuated by the spindle for resetting the counter group.

In testimony whereof I affix my signature in presence of two witnesses.

JACOB J. ALBRIGHT.
